Primary Examiner — John Windmuller*Assistant Examiner* — Steven Czyz(74) *Attorney, Agent, or Firm* — Fasken Martineau DuMoulin, LLP(57) **CLAIM**

The ornamental design for a grate, as shown and described.

DESCRIPTION

FIG. 1 is a perspective view taken from a top, front, left side of a grate;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof; and,

FIG. 7 is a left side elevation view thereof.

The broken lines in the figures represent portions of the article that form no part of the claimed design.
